FLOW PROPORTIONING APPARATUS

Herbert Ziebolz, Chicago, Ill., assignor to Askania
Regulator Company, Chicago, Ill., a corporation
of Illinois

Application July 9, 1941, Serial No. 401,667

7 Claims. (Cl. 137—164)

This invention relates to improved apparatus for supplying combustion supporting air by conduit means as a function of the theoretical air requirements of a plurality of separate fuels having different theoretical air requirements and heating values while at the same time augmenting or diminishing such theoretical supply by an amount which depends on other factors which may or may not vary in accordance with the rates of fuel flow and in which the flow of at least one of the fuels is adapted to be automatically controlled; and the flow of the other fuel varies. The main idea is to provide improved summarizing and proportioning means, including automatic control means for the flow of at least one of the fuels, whereby the air flow may be varied automatically in response to changes in the flow of the other fuel or fuels to produce a desired combustion atmosphere in a furnace or the like. The problem is to so adjust the controlled supply of air that a desired percentage of excess or deficiency of air is provided regardless of the variations in the ratios of the fuels and of their rates of flow. By "controlled supply" of air is meant the air which is introduced through air-conduit means independently of air admitted with the fuel and/or air which enters into a furnace by infiltration and from other uncontrollable sources.

Heretofore, it has been suggested that rates of fuel flow be summarized by means of fuel flow meters or by pilot air flows which are directly proportional to the individual B. t. u. rates of fuel flow and the total air proportioned to the sum of the individual fuel flows in terms of their heating values. The design of such mechanisms is based on the fact that a definite amount of air is required for theoretically complete combustion of a given quantity of fuel in terms of its B. t. u. value. In the operation of industrial furnaces or boiler furnaces a number of factors must be taken into consideration which renders the supply of the calculated or exact amount of air necessary for theoretically complete combustion improper. Such factors do not vary as a direct function of the rate of fuel flow but present different values at different rates of fuel flow. Some of these factors are, for example, air used to atomize liquid fuels or primary air used for conveying pulverized fuel, which air is not subject to control by the well known air control apparatus. Such factors may be termed "burner factors." The calculated amount of air, which would be supplied by the control apparatus to support theoretically complete combustion of a single fuel, modified by the amount of air which finds its way into the burner installation by reason of these factors, is referred to herein as "compensated air requirements" of that fuel. If more than one fuel

is supplied, the calculated amount of air which would be supplied by the control apparatus to support theoretically complete combustion of the plurality of fuels, modified by the amount of air which finds its way into the burner installation, as a result of the feeding of more than one fuel, is referred to herein as "totalized compensated air requirements" for the fuels. Further correction factors may be necessary in any furnace installation to take into account infiltration of air into the furnace, other sources of air of determinable amounts admitted to the furnace, or the desired condition of the furnace atmosphere. All of these factors are subject to variations which are not direct functions of the rate of total fuel supply. They may be termed furnace factors. These furnace factors may require further adjustment in the "total compensated air requirements" called for by the fuels. The total compensated air requirements, thus modified by these furnace factors, is herein termed "adjusted total air requirements."

It is therefore a further and more specific object of this invention to provide automatic control and proportioning means which takes into account all such variable factors and varies the total supply of air as a function of the sum of the flows of at least one primary fuel, supplied at a constant rate, and a secondary fuel supplied at a variable, uncontrolled rate.

This invention involves certain improvements over my copending application Ser. No. 401,666, filed July 9, 1941.

Other aims and advantages of the invention will appear in the specification, when considered in connection with the accompanying drawing, wherein the figure is a diagrammatic illustration of one form of apparatus embodying the invention applied to the control of air for two fluid fuels.

Referring particularly to the drawing, the control mechanism is shown as being applied to control the amount of combustion supporting air in accordance with the compensated air requirements for two separate fuels of different character flowing through individual conduits 10 and 11 and the combustion air is supplied for both fuels through a single conduit 12, the conduits leading to a furnace, not shown. One of the fuels, for example, may be fuel oil, the supply of which is to be maintained constant, and the other may be coke oven gas, the supply of which is variable, depending upon the demand for heat in a furnace or boiler.

In this instance, the flow of primary fuel in conduit 10 is adjusted manually and maintained constant by means of a regulator. The conduit 10 is shown as having a constriction 13 and a butterfly control valve 14. The position of the valve is adapted to be automatically varied and

the flow maintained by a jet pipe regulator 15, here shown as being of the well known hydraulic type. A pair of pipes 16 and 17 are connected to opposite sides of the constriction and lead to opposite sides of a diaphragm 18 connected to act on one side of the pivoted jet pipe 15. The force exerted by the diaphragm acts in opposition to a spring 19, the compression of which is controlled by a movable cam 20 of variable contour. The cam is shown as being composed of a multiplicity of relatively adjustable, slotted pieces clamped together by a bolt 21 and secured to a carriage 22 which is slidably mounted in fixed bearings. The contour of this cam is adjustable to take into account the foregoing variable factors involving the fuel so that the adjusting movements are always proportional to the compensated air requirements for the fuel, departing from a directly proportional relationship between the theoretical amount of air called for and the rate of flow of the fuel. The regulator has a ratio slider 23 which may be employed to vary the ratio of the compensated air requirements for the fuel in accordance with variations in the density, chemical analysis and viscosity of the fuel, as well as other factors. The force exerted on the jet pipe by the diaphragm due to the differential pressure on opposite sides of the constriction 13 is always counterbalanced by the force of the spring to restore the jet pipe to neutral position and maintain the flow of fuel constant. The carriage 22 on which the cam 20 is mounted, is adapted to be adjusted longitudinally by means of a hand wheel 24 carrying a pinion meshing with a rack 25 connected to the carriage. Of course, the manual adjustment may be effected in any one of a number of ways.

The cam 20 is set so that its adjusting movement from a zero position representing zero fuel flow corresponds with the compensated amount of air for the first or primary fuel supplied at any desired constant rate and the rate of flow of the fuel is maintained by the regulator, the jet pipe of which acts through a pair of pipes 26 and 27 on the piston 28 of a servo-motor connected to the butterfly valve 14 to maintain the rate of fuel flow through the orifice constant. The adjusted position or movement of the cam is indicated by means of a pointer 29 cooperating with a scale 30 reading in terms of the compensated quantity of air for the fuel or fuel rate. The carriage is shown as being connected by means of an arm 31 and link 32 to a crank arm 33 mounted on one shaft of a differential gear 34. Such a differential gear is shown in detail in my aforesaid copending application.

The conduit 11 for the second fuel is also shown as having a constriction 35 across which differential pressure is created to operate a flow responsive device having a jet pipe 36 through pipes 37 and 38 and a diaphragm 39 in the same manner as the jet pipe 15. The force exerted by the diaphragm on the jet pipe is opposed by a spring 40, the compression of which is controlled by an adjustable cam 41 made of a plurality of pieces like cam 20 and its adjusted contour is determined by the compensated air requirements for the second fuel at its different rates of flow or for each increment of change in its rate of flow. The flow responsive device also has a ratio slider 42 adapted to change the percentage or ratio of the air to the fuel. In addition, the ratio slider permits the introduction of correction factors

which take into account variations in the chemical analysis of the fuel, viscosity changes, density changes, etc. The jet pipe is shown as operating a servo-motor 43 of the piston type through a pair of pipes 44 and 45. The cam 41 is mounted on a carriage 46 which is slidably mounted in fixed bearings similar to carriage 22. The carriage has a rack 47 meshing with a gear 48 which is operated by the servo-motor 43 through a crank 49. The carriage is also shown as operating a pointer 50 cooperating with a scale 51 which is calibrated in terms of the compensated air requirements for the second fuel. The arrangement is such that a definite relation between the flow impulses and the movement of the cam 41, indicated by pointer 50, is established. This relation can be varied to suit the individual furnace conditions by varying the contour of the cam. Any change in the position of the ratio slider increases or decreases the stroke of the cam 41 directly proportional to impulses throughout the fuel flow range.

The carriage 46 is likewise connected to the differential gear 34 by means of an arm 52 and link 53 through a second crank arm 54 on the second shaft of the differential gear. As explained in the aforesaid application, the differential gear summarizes the adjusted and variable movements of the two cams and the sum of these movements is imparted through it to a spur gear 55, which operates a rack 56 on a slideable carriage 57, similar to the carriage 46. The carriage 57 also carries a cam 58 made like cams 20 and 41 and which is shaped to proportion the supply of air in accordance with the movements imparted to it and to take into account air infiltration into the furnace. In other words, its contour is adjusted to vary the proportion between the total compensated air requirements and the adjusted total air requirements for each increment of change in the total fuel flows. The carriage operates a pointed 59 cooperating with a scale 60, to indicate the sum of the total, compensated air requirements of the separate fuels before the movement imparted to the gear 55 and, through it, to the cam 58 is the sum of the movements imparted by the separate cams 20 and 41 through the differential gear 34.

Now, the flow of air in conduit 12 is shown as being controlled by a butterfly valve 61 which is actuated by a piston type servo-motor 62. The servo-motor is connected by pipes 63 and 64 to be operated by a jet pipe regulator 65, also having a ratio slider 66 whereby the air ratio may be changed at will. The cam 58 acts on one side of the jet pipe through a spring 67 and changes the setting of the regulator to control the air flow through the conduit 12. The spring 67 acts on the jet pipe in opposition to a diaphragm 68 on the opposite side of the jet pipe, and the position of the diaphragm is controlled by the pressure differential across a constriction 69 in the air conduit 12 acting through pipes 70 and 71 on opposite sides of the diaphragm.

As the spring is compressed by the movement of the cam to the right, the jet pipe turns clockwise and thereby causes the servo-motor to open the valve 61 until the increase in air flow creates a differential pressure across the constriction 69 which is sufficient to counterbalance the force of spring 67. Thus, the air flow is so controlled that it is directly proportional to the air cam movement, as modified by the compensating adjustments, which movements are directly proportional to the sum of the individual compensated

air requirements of the individual fuels. The adjustments of the ratio slider 66 permit variations in the ratio between the controlled air flow and the total compensated air requirements, thus controlling the percentage of excess or deficiency of the total air.

In the operation of the apparatus, the hand wheel 24 is used to set the first fuel cam 20 in terms of the rate of flow of compensated air requirements, as observed on the scale 38, to maintain a desired rate of fuel flow. This adjustment imparts movement through the arm 38 on one shaft of the differential gear to the air cam 58 and the cam 20 remains fixed in its adjusted position, due to friction of the parts. As the flow of the second fuel in the conduit 11 changes, the flow responsive device operates the servo-motor 43 and thus imparts control movement through the arm 54 on the second shaft of the differential gear which is added to the adjusted movement of the first shaft and thus additionally moves the air cam 58 to change the control setting of the air flow regulator 68. This setting will correspond to the total compensated air requirements for the first and second fuels and will be varied automatically as the flow of the second fuel varies.

It will be understood that the regulators, flow responsive device servo-motors and the cams may be mounted on any suitable support, such as a table. The stroke of the cams can be made the same for all controls by choosing the necessary gear ratio of the differential gears and the cams may be guided for straight line movement in any convenient manner, for example, by wheeled carriages or the like. Moreover, the indicators may be either mechanical or electrical and all of them may be located at any convenient point.

It will be understood that the improved apparatus embodying the invention may be applied to the control of the combustion air for any number of fuels by using an additional differential gear for each additional fuel as disclosed in the aforesaid copending application.

Obviously, the present invention is not restricted to the particular embodiment thereof herein shown and described. Moreover, it is not indispensable that all the features of the invention be used conjointly, since they may be employed advantageously in various combinations and sub-combinations.

What is claimed is:

1. Apparatus for proportioning the supply of combustion air to that of separate fuels having different heating values comprising, in combination, individual conduits for the air and fuels; a regulator connected to one of the fuel conduits to control the flow therein; a manually movable control member associated with and connected to set the regulator to maintain the fuel flow constant at a predetermined rate; said member being so constructed and arranged that its total movement from a zero position corresponding to zero fuel flow is proportional to a compensated quantity of air corresponding to the rate of flow of the fuel; a flow responsive device connected to a second fuel conduit through which the rate of flow varies and arranged to be operated by impulses derived from the flow of the second fuel; control means, in-

cluding a member connected to the flow responsive device, to convert said impulses into control movements of said member from a zero position corresponding to zero flow of the second fuel, which movements are directly proportional to compensated quantities of air for the second fuel at its varying rates of flow; summarizing means connected to the manually movable member and the control means to summarize said movements; and a regulator controlled by said summarizing means and connected to said air conduit to vary the supply of air.

2. Apparatus, as set forth in claim 1, wherein the manually movable control member has adjustable elements arranged to be adjusted so as to produce different settings of the regulator for any given amount of manual movement of the control member.

3. Apparatus, as set forth in claim 1, wherein the manually movable control member has adjustable elements arranged to be adjusted so as to produce different settings of the regulator for any given amount of manual movement of the control member, and wherein a cam of adjustable contour and shaped to allow for air infiltration into the furnace is connected to be actuated by the summarizing means to operate the regulator which is controlled by said summarizing means, and wherein the last mentioned regulator is provided with means to multiply the adjusted total air flow by any given factor.

4. Apparatus, as set forth in claim 1, wherein in the fuel regulator and the flow responsive device are of the hydraulic type having jet pipes and the manually movable control member to set the fuel regulator, and the control means connected to the flow responsive device both comprise spring loading cams of adjustable contour to make compensations in the theoretical air requirements for the respective fuels.

5. Apparatus, as set forth in claim 1, wherein in the regulator controlled by the summarizing means is of the hydraulic type having a movable jet pipe and a loading cam of adjustable contour and is directly operated by said summarizing and connected to operate the regulator, the contour of said cam being adjustable to call for an adjusted total amount of air for each increment of its movement thereby allowing for air infiltration in to a furnace.

6. Apparatus, as set forth in claim 1, wherein in the fuel regulator is provided with ratio varying means so constructed that the movement of the manual control member may be multiplied by a given factor for any constant ratio of fuel flow, and wherein the flow responsive device also includes a ratio varying member to multiply the control movements imparted thereby to its associated member by a given factor for all ratios of flow of the second fuel.

7. Apparatus, as set forth in claim 1, wherein the manually movable control member has adjustable elements arranged to be adjusted so as to produce different settings of the regulator for any given amount of manual movement of the control member, and wherein an indicator is associated with said manually adjustable control member.

HERBERT ZIEBOLZ.
